UNITED STATES PATENT OFFICE.

HENRY J. DAVIES, OF BROOKLYN, NEW YORK.

DESIGN FOR CLOCK-STAND.

SPECIFICATION forming part of Design No. 12,251, dated May 10, 1881.

Application filed April 1, 1881. Term of patent 7 years.

To all whom it may concern:

Be it known that I, HENRY J. DAVIES, of Brooklyn, in the county of Kings and State of New York, have originated and produced a new and Improved Design for Clock-Stands, 5 of which the following is a specification.

The character of my design is clearly illustrated in the accompanying drawing, which represents a front elevation of the clock-stand.

10 As clearly shown, the most prominent feature of the design is an obelisk, A, which is erected upon a base, B, and is covered upon its front face with hieroglyphics. The dial or front C of the clock-case is placed at the front 15 of the obelisk, at a considerable distance from the base. Below the clock-dial is a fanciful ornament consisting of a globe, a, flanked upon each side by birds and wings b, and below the globe and between the birds and wings is a 20 pendent ornament, c. The dial or front C is surmounted by a winged ornament, D, of fanciful design. Upon one side of the obelisk, and standing upon the base, is a figure, E, of a man in the garb of ancient Egypt, with one 25 hand holding a chisel against the obelisk, and the other uplifted and carrying a mallet. The figure E is accompanied by a bird, F, representing the ancient bird Isis of the Egyptians. Upon the side of the obelisk, opposite the figure 30 E, is a figure, G, of a man in modern garb, with one hand behind his back and carrying a scroll, and the other hand uplifted. The figure G is accompanied by the figure of a dog, H. In the center of the base B are the figures "1881,"

and these are flanked on the left hand by the 35 word and letters "Egypt B. C." and on the right hand by the letters and words "A. D. New York." On the front of the obelisk, below the dial C, is a thermometer, I.

What I claim, and desire to secure by Letters Patent, is—

1. The design for a clock-stand, consisting of the obelisk, the dial or front arranged upon the front face thereof, and the ornaments a b c D above and below said dial or front, as shown 45 and described.

2. The design for a clock-stand, consisting of the obelisk and base, and the Egyptian figure upon one side of the obelisk, as shown and described.

3. The design for a clock-stand, consisting of the obelisk and base, the figure in modern garb upon one side of the obelisk, as shown and described.

4. The design for a clock-stand, consisting of 55 the obelisk A, base B, the dial C, the Egyptian figure E, and bird F, as shown and described.

5. The design for a clock-stand, consisting of the obelisk A, the base B, and the figure G and dog H, as shown and described.

6. The design for a clock-stand, consisting of 60 the obelisk A, the base B, the dial C, the Egyptian figure E, and bird F, and the figure G and dog H, as shown and described.

HENRY J. DAVIES.
